UNITED STATES PATENT OFFICE.

HERBERT A. CONNERS, OF BOSTON, MASSACHUSETTS.

LIFTING-JACK.

1,144,933.

Specification of Letters Patent. Patented June 29, 1915.

Application filed February 7, 1914, Serial No. 817,834. Renewed January 29, 1915. Serial No. 5,124.

To all whom it may concern:

Be it known that I, HERBERT A. CONNERS, a citizen of the United States, and resident of Boston, county of Suffolk, Commonwealth of Massachusetts, have invented an Improvement in Lifting-Jacks, of which the following description, in connection with the accompanying drawings, is a specification, like characters on the drawings representing like parts in each of the several views.

10 This invention relates to lifting jacks, and while having other and more general fields of usefulness is well adapted and designed for use in lifting automobile axles and similar work.

15 A prime object of the invention is to provide an improved jack of relatively compact dimensions, that is, of small height when the plunger is run in or collapsed, while having at the same time a relatively long lift.

20 A further object of the invention is to provide a jack with these characteristics that is exceptionally simple and cheap in construction and at the same time strong and efficient in use.

25 A still further object is to provide a jack of this type that has exceptionally great lifting capacity in proportion to the power required, by reason of frictional and like resistance being minimized by the application of the power direct to the lift.

30 The above and other objects and features of the invention will be better understood from the following detailed description taken in connection with the accompanying drawings and will be thereafter pointed out in the appended claims.

35 Referring to the drawings: Figure 1 is a front elevation of a jack constructed in accordance with my invention, parts being sectioned away to better show the interior construction; Fig. 2 is a side elevation thereof with parts also sectioned away; Fig. 3 is a plan view, and Fig. 4 is a vertical section partly broken away showing the jack with plungers run out.

40 The base of the jack is indicated at 10 as an upright housing which is shown as rectangular and oblong in cross section. This housing has slidably fitted therein a bar or block 11 which is adapted to telescope wholly within the housing or to be projected outward therefrom at will, constituting a secondary plunger as presently described. The block or secondary plunger 11 is hollowed

out lengthwise to receive an inner rectangular primary plunger 12, this plunger having a reduced front portion 13 which extends out flush with the front of the block 11 and interfits with retaining flanges 14 at the front of the block 11. The plunger 12 has rack teeth 15 throughout the height thereof which engage with teeth of a long spur pinion 16 journaled at 17 in the front of the housing near the top thereof. The pinion 16 has at one end a shaft extension 18 squared as at 19 to receive a crank or like operating device, while a similar shaft extension at the other end of the pinion has fixed 50 thereon a ratchet wheel 20 with which cooperates a pawl 21 pivoted to the housing at 22 to prevent backward turning of the pinion except when the pawl is tripped.

55 It is to be observed that the teeth 15 of plunger 12 extend up so that the upper ones thereof engage the pinion 16 when the plunger is in lowermost position so that it may be run out as required merely by turning the pinion 16. The front of block 11 at the 60 sides of the plunger is also equipped with rack teeth 23 adapted to engage the teeth of pinion 16, but when the block is in lowermost position as seen in Fig. 1 of the drawings, the topmost ones of these teeth terminate just short of the pinion 16 so that they are not engaged thereby.

65 The bottom of plunger 12 is equipped with means to engage the block 11 when the plunger is nearly run out, and for this purpose I show lateral lugs 24 which move in grooves 25 provided therefor in the block 11, there being shoulders 26 at the ends of these grooves near the top of the block with which the lugs 24 engage when the 70 plunger is nearly run out. As this occurs, the final movement of the plunger 12 picks up the block 11 and lifts it enough so that the topmost ones of the teeth 23 come into engagement with the teeth of pinion 16 75 so that the block is then under control of the pinion 16 to be lifted thereby. As this occurs a dog 27 pivoted at 28 to the top of block 11 is pressed into a notch 29 near the lower end of plunger 12 by a spring 30 80 housed in the top of the block, this notch having a horizontal stop shoulder at its top which thus locks the plunger to the block and causes it to continue to move upward with the block as the block is lifted. It 85 will be observed that as this occurs the plunger 12 still has some little extent of bearing

engagement with the block 11 so that it is securely held and supported laterally as well as vertically thereby. The dog 27 has a handle 31 extending without the housing 5 so that it may be conveniently tripped to permit the plunger to be run back. The top of the housing is shown as equipped with a front holding flange or bar 32 at its top with which the plunger and slide block 10 engage so as to be properly guided in their sliding movement out from and back into the housing. It is to be noted that the top 33 of plunger 12 is adapted to be run back entirely within the housing so that the jack 15 is very compact and of relatively small height when the plunger is run in.

It is to be observed that in the use of my improved jack the application of power is made directly to the lifting element, both 20 during the initial lifting of plunger 12, and during the lifting of the block or secondary plunger 11 carrying with it the plunger 12, and that in this second lifting movement there are no additional parts that have to be 25 lifted, nor any additional gearing required, so that the device is at once exceptionally simple and particularly efficient.

I am aware that details of construction, such as the specific character of the operating device can be varied without departing 30 from the spirit of the invention and I therefore desire the present embodiment to be considered as illustrative and not restrictive and refer rather to the appended claims 35 to indicate the scope of the invention.

Having described my invention, what I claim as new and desire to secure by Letters Patent is:

1. A lifting jack, comprising a base support, a plunger mounted for in and out movement relative thereto, an operating device connected with said plunger, and a slideable member normally disconnected from 40 said operating device having connection with said plunger to be brought into operative relation to the operating device as the plunger nears the outer limit of its movement; whereby it may be moved out from the base by said operating device, there being provision whereby the plunger is then locked to said member to be moved farther outward.

2. A lifting jack, comprising a base support, a primary plunger mounted for movement in and out relative thereto, an operating device for said primary plunger, and a secondary plunger slidably mounted in the base and also in slideable relation to the primary plunger, said secondary plunger having pro-

vision for connection to said operating device, normally in inoperative position, interengaging means on said primary plunger and secondary plunger whereby the secondary plunger is picked up by the primary plunger near the end of its outward movement and brought into operative relation to said operating device for farther outward movement, and means associated therewith for locking the primary plunger to the secondary plunger on such farther outward movement.

3. A lifting jack, comprising a base, primary and secondary plungers slidably fitted in said base and also mounted for limited sliding movement with respect to each other, 75 an operating device mounted on the base, means on both of said plungers for engaging said operating device, such means on said secondary plunger being normally disconnected from the operating device, there being interengaging portions on said primary and secondary plungers, whereby the former picks up the latter near the limit of its outward movement and engages it with said operating device for farther outward movement, and a dog on one of said plungers mounted to engage a notch on the other to lock them together when the primary plunger is extended and being moved outward by the secondary plunger.

4. A lifting jack, comprising a base support, primary and secondary plungers slidably mounted in said support and one mounted for limited sliding movement relative to the other, said plungers each presenting a plane front face equipped with rack teeth, such teeth on the primary plunger being extended up beyond those on the secondary plunger, an elongated pinion mounted to engage the teeth of the primary 100 plunger and normally out of engagement with the teeth of the secondary plunger, there being means whereby the primary plunger picks up the secondary plunger near the limit of its outward movement to 105 bring its teeth into operative relation to said pinion, means for then automatically locking the primary plunger to the secondary plunger, and means for holding said plungers in the position to which they are 110 run out.

In testimony whereof, I have signed my name to this specification, in the presence of two subscribing witnesses.

HERBERT A. CONNERS.
